ELECTRIC SOCKET

Joseph D. Ceader, Cleveland Heights, Ohio, assignor to General Electric Company, a corporation of New York

Application February 3, 1937, Serial No. 123,755

14 Claims. (Cl. 173—346)

The present invention relates to electric sockets having provisions for preventing short-circuit between the terminals of the socket when the socket is empty. One use of sockets of this type is for Christmas tree lights where the conventional socket is likely to be short-circuited by pieces of tin foil dropping between the exposed terminals of the empty socket.

The object of my invention is to provide an improved construction for sockets of this type and for a consideration of what I believe to be novel in my invention, attention is directed to the accompanying description and the claims appended thereto.

In the accompanying drawing Fig. 1 is an elevation of a socket embodying my invention showing a lamp in the socket; Fig. 2 is a sectional elevation at right angles to Fig. 1 with one-half of the base removed and showing the lamp in the socket; Fig. 3 is a view similar to Fig. 2 with the lamp removed; Fig. 4 is a sectional view similar to Fig. 1 with the lamp removed; Fig. 5 is a sectional elevation of a modification; Fig. 6 is a perspective view of a part of the socket shown in Fig. 5; and Fig. 7 is an elevation of another modification of my invention.

Referring to the drawing the numeral 1 indicates a screw shell which serves as one terminal for the socket. The shell is carried within a base which comprises parts 2 and 3 of molded insulating material which are held together by a U shaped spring clip 4 which fits in the grooves 4a. The base is split along the axis of the shell so that the base may be assembled around the shell. One of the arms of the clip 4 is provided with a tang 5 and the other arm is provided with a rounded projection 5a which fits into depressions in the parts of the base and prevents easy removal of the clip. From the rounded projection 5a of the clip extends an arm 6 which cooperates with the base to provide a clip for supporting the socket. This clip is particularly useful in the case of sockets for use on Christmas trees since the clip 6 may be fastened over a branch of the tree.

At the lower end of the base the abutting surfaces of the parts of the base are provided with spaced transverse grooves 7 for clamping a pair of conductors 8 between the parts of the base. One of the conductors is connected to a contact 9 which serves as the center terminal of the socket. This contact is provided with tangs 10 (see Fig. 4) which extend on either side of the conductor and are electrically connected thereto by squeezing the tangs together. The other

conductor is similarly connected to a contact 11 which is adapted to engage the shell 1 which serves as the other terminal of the socket. The tangs of the contact 11 extend over both of the conductors but are electrically connected to only the lower conductor. With this arrangement the contact 11 serves to prevent displacement of the conductors. The conductors 8 are adapted to form the respective conductors of a string of parallel connected Christmas tree lights.

The center terminal 9 extends through an opening provided by complementary grooves 12 in the parts 2 and 3 of the base into a recess 13 in the base. The contact 11, likewise, extends into the recess 13 through complementary grooves 14 formed in the parts of the base. The grooves 12 and 14 hold the contacts 9 and 11 in place. The inner surface of the recess 13 is provided with threads 14a which cooperate with the threads 15 on the screw shell 1. The friction between the threads 14a and 15 is such that the shell is threaded into and out of the base by a plug 16 threaded into the shell. That is, the friction between the threads of the plug 16 and the threads of the shell is greater than the friction between the threads of the shell and the threads 14a of the base. The lower end of the shell 1 has a smooth portion 17 so that the shell cannot be threaded outward beyond the position shown in Fig. 3. The contact of the threads 14a of the base with the smooth portion 17 of the shell provides a stop which limits the outward movement. When the shell is in the outer position, there is a wedging action between the threads 14a and 15 which tends to separate the parts 2 and 3 of the base. The pressure exerted by the parts of the base on the shell holds the shell firmly in its outer position so that it will not be moved inward by jarring the socket. In the bottom of the shell is a disk-shaped member 18 of insulating material having an opening 19 therein for the center terminal 9 of the socket. The disk 18 is held in place by spinning the shell against the outer edge of the disk. Beneath the disk 18 extends a flange 20 of the shell which is adapted to make electrical contact with the contact 11 when the shell is threaded into the base. This contact is broken when the shell is threaded out of the base as shown in Fig. 3. When the shell is in the outer position, it is, therefore, electrically insulated from the conductors and the member 18 prevents contact with the center terminal 9 of metal particles such as tin foil which fall into the shell. When the shell is in the

outer position, it projects above the base but since in this position it is electrically insulated, there is no danger to the user.

Prior to inserting a lamp in the socket, the shell 1 is in the position shown in Fig. 3. In the use of the socket the plug 16 of a lamp is threaded into the shell 1. The plug is threaded into the shell until the friction between the threads on the plug exceeds the friction between the threads 15 on the shell and the threads 14a on the base. As soon as this condition obtains the shell is threaded into the base without further threading of the plug into the shell until the shell reaches the position shown in Fig. 2. In this position 10 contact is made between the flange 20 on the shell and the contact 11 in the base and the center terminal 9 in the base projects into the opening 19 in the insulating member 18. Further 15 turning of the plug 16 causes the plug to be threaded into the shell until it reaches the position shown in Fig. 2. In this position the center contact 21 of the plug makes contact with the center terminal 9 of the base.

During the removal of the plug from the shell, 25 the shell is first unthreaded from the base until it reaches the position shown in Fig. 3. This is due to the greater friction between the threads of the plug and the threads of the shell. After the shell reaches the position shown in Fig. 3, the plug 30 is unthreaded from the shell to completely remove the plug from the socket.

In Figs. 5 and 6 is shown a socket having another arrangement for moving the shell into and out of the base as a plug is threaded therein. In 35 this construction the base or husk 21 is a tubular part molded from suitable insulating material. In the upper end of the base is a cylindrical recess 22 in which is fixed a disk 23 carrying spring contacts 24 and 25. The disk is pressed against 40 a shoulder 26 at the bottom of the recess. The contact 24 is located at the center of the disk 23 and is riveted thereto by a rivet 27 which also serves to secure a terminal 28 to the disk. The terminal 28 is located on the underside of the disk 45 and is intended to be connected to a line conductor. The contact 25 is located near the periphery of the disk 23 and is riveted thereto by a rivet 30 which likewise secures a terminal 31 to the underside of the disk. In the use of the socket, one of 50 the line conductors is connected to the terminal 28 and the other line conductor is connected to the terminal 31. The line conductors extend through an opening 32 in the lower end of the base 21, and if desired, the space around the conductors and the terminals 28 and 31 may be filled 55 with a suitable cement to hold the conductors in place. The manner of connecting the line conductors to the terminals 28 and 31 is not shown, it being well understood in the art.

60 Slidably mounted in the recess 22 is a sleeve 33 of molded insulated material in which is fixed a socket shell 34. The socket shell is provided with a flange 35 at its upper end which frictionally engages the side walls 36 of the sleeve and holds 65 the shell therein. The lower end of the shell 34 is closed by a disk 37 of insulating material which is held in place by a spunover flange 38 on the shell. The flange 38 is above the contact 25 and is adapted to cooperate therewith to complete the 70 electrical connection to the socket shell when the shell is moved inward from the position shown in Fig. 5. At the center of the disk 37 is a rivet 39 which serves as the center contact or terminal of the shell, and when the shell is moved inward 75 from the position shown in Fig. 5, makes an elec-

trical connection with the contact 24. In the outside of the sleeve 33 is a groove 40 into which extends a pin 41 which is fixed in the side wall of the base 21. The pin 41 is fixed in the base after the sleeve 33 has been assembled therein. It, 5 therefore, serves to hold the parts in assembled relation. The pin 41 and the groove 40 also serve as a cam means for guiding the movement of the socket shell into and out of the base as the sleeve 33 is turned relative to the base. When the shell 10 is empty, the parts occupy the position shown in Fig. 5 in which flange 38 of the shell and the contact 39 are separated and therefore electrically insulated from the contacts 25 and 24 respectively. The socket is now protected from short-circuit since there is no electrical connection to shell 34 and the contact 37 which constitute the exposed terminals of the socket. In this position the pin 41 rests in a depression 42 in the groove 40. The depression 42 tends to hold the 20 sleeve 33 in its outer position so that it may not be accidentally moved inward, for instance, by jarring of the socket. When a plug is threaded into the shell 34, the shell remains stationary until the friction between the threads on the plug 25 and the threads on the shell exceeds the force required to turn the sleeve 33 relative to the pin 41. The force required to turn the sleeve relative to the base is determined by the shape of the depression 42 which is chosen so that force due to 30 friction between the plug and the shell exceeds the force required to turn the sleeve in the base when the plug is partially threaded into the shell. As soon as this condition is reached, further turning of the plug causes the sleeve 33 to be turned 35 relative to the base until the pin is in the vertical portion of the groove 40 after which an inward pressure on the plug will cause the pin to be moved inward until the contact 39 makes contact with the contact 24 and the flange 38 makes contact with the contact 25, thus completing the 40 electrical connection to the terminals of the socket. Further rotation of the plug causes the pin to be rotated to the end of the upper horizontal portion of the groove 40, holding the shell 45 stationary so that the plug is threaded into the shell 34 until the center terminal of the plug makes contact with the contact 39, thus completing the electrical connection to the plug.

When the plug is turned to unthread it from 50 the shell, the first effect will be to cause the sleeve 33 to be turned in the base so as to be moved outward, thereby breaking the circuit from the socket terminals to the contacts 24 and 25. The outward movement of the sleeve 33 will be assisted 55 by the force derived from the spring contacts 24 and 25. It is obvious that this spring means may be used. The outward movement of the sleeve may also be assisted by pulling on the plug as it is unthreaded. When the sleeve reaches its outer position, the pin 41 fits in the depression 42. In this position further rotation of the sleeve is prevented and continued turning of the plug will cause the plug to be unthreaded from the shell.

In Fig. 7 is shown another modification of my 65 invention. The greater portion of this socket is of the same construction as the socket shown in Figs. 1 to 4 inclusive and corresponding parts are denoted by the same reference numerals. In this construction accidental contact with the 70 center terminal 9 is prevented by a spring 43. The spring 43 is integral with a disk 44 which rests in the bottom of a recess 45 in the base. On the upper side of the disk 44 is a disk 46 of insulating material over which extends a flange 75

47 on the contact 11. The contact 11 therefore serves to hold the disks 44 and 46 in place. On the side walls of the recess 45 is a helical projection 48 which cooperates with the external threads 49 on a screw shell 50. The friction between the projection 48 and the threads 49 is less than the friction between the screw shell 50 and a plug threaded therein so that the screw shell is moved into and out of the base in the same manner as in the socket shown in Figs. 1 to 4 inclusive. Outward movement of the screw shell is limited by a flange 51 which engages a shoulder 52 on the base. When in its inner position a flange 53 on the screw shell makes contact with the flange 47 on the contact 11 and the spring 43 projects through an opening 54 in the bottom of the screw shell. When a plug is completely threaded into a screw shell the center terminal of the plug engages the spring 43 and compresses it against the contact 9 thereby completing the electrical connection.

Prior to inserting a plug into the socket the parts occupy the position shown in Fig. 7. In this position the electrical connection to the screw shell 50 is broken and the spring 43 is separated from the contact 9. Pieces of tin foil which may fall into the open socket are therefore prevented short-circuiting the socket. When a plug, for example, the plug 16, of a lamp is threaded into the shell it turns relative to the shell until the friction between the threads on the plug and the threads in the shell exceeds the friction between the threads on the shell and the projection 48. As soon as this condition is reached, the shell is threaded into the base without further turning of the plug relative thereto until the flange 53 on the shell is firmly seated against the flange 47 on the contact 11. This completes the electrical connection to socket shell. Further turning of the plug now causes the plug to be threaded into the shell until the center terminal of the plug 16 forces the spring 43 into engagement with the contact 9 and completes the electrical connection to the plug.

During the removal of the plug from the shell, the shell is first unthreaded from the base until it reaches the position shown in Fig. 7. This is due to the greater friction between the threads of the plug and the threads on the shell. After the shell reaches its outer position with its flange 51 against the shoulder 52, further turning of the plug causes it to be unthreaded from the shell.

What I claim as new and desire to secure by Letters Patent of the United States, is:

1. In an electric socket, a base, a center terminal for co-operating with the center contact of a plug to be inserted in said socket, a screw shell rotatably and axially movable in the base, a part on the base engaging the threads on the outside of the screw shell whereby the shell is moved into and out of the base upon rotation therein, the friction between said part of the base and the screw shell being less than the friction between the screw shell and the plug threaded therein whereby the shell may be rotated by the plug, means stopping outward movement of the shell prior to disengagement of said part and the shell whereby the plug may be unthreaded from the shell, and a contact in the base engaged by the shell when the shell is threaded into the base, said contact being spaced from the shell when the shell is threaded out of the base.

2. In an electric socket, a base, a center ter-

5 minal for co-operating with the center contact of a plug to be inserted in said socket, a screw shell rotatably and axially movable in the base, cooperating parts on the screw shell and the base arranged to effect axial movement of the screw shell into and out of the base upon rotation of the screw shell in the base, the resistance to rotation of the screw shell being such that the screw shell is rotated in the direction to move it inward by threading the plug into the shell and such that the screw shell is rotated in the direction to move it outward by threading the plug out of the shell, means stopping the outward movement of the shell prior to disengagement of said parts whereby the plug may be unthreaded from the shell, and a contact in the base engaged by the shell when the shell is in its inner position, said contact being spaced from the shell when the shell is in its outer position.

3. In an electric socket, a base, a center terminal for co-operating with the center contact of a plug to be inserted in said socket, a screw shell rotatably and axially movable in the base, cooperating parts on the screw shell and the base arranged to effect axial movement of the shell into and out of the base upon rotation of the shell with respect to the base, said cooperating parts limiting the outward movement and rotation of the shell, and a contact in the base engaged by the shell when the shell is moved inward in the base, said contact being spaced from the shell when the shell is moved outward in the base.

4. In an electric socket having a center terminal and a screw shell comprising the other terminal of the socket, a member movable to an inner position permitting contact between the terminals of the socket and the terminals of a plug threaded therein and movable to an outer position protecting the terminals of the socket from short-circuit, interengaging means whereby said member is moved to its inner and outer positions upon rotation relative to the socket, said means being engaged when said member is 45 in its outer position and serving to prevent rotation of said member, and means whereby the rotation of said member to move it to its inner and outer positions is effected by threading a plug into and out of the shell.

5. In an electric socket having a center terminal and a screw shell, a base, said shell and base having pin and slot means whereby the shell is movable into and out of the base upon rotation relative thereto, and a contact on said 55 base arranged to be engaged by said shell when the shell is in its inner position, said contact being spaced from the shell when the shell is in its outer position.

6. In an electric socket having a center terminal and a screw shell for cooperation with a plug threaded in the shell, a base, said shell and base having cooperating parts whereby the screw shell is moved into and out of the base upon rotation relative thereto, said parts being engaged when the shell is in its outer position and serving to prevent rotation of said shell, the resistance to rotation of the shell being less than the friction between the threads of the shell 65 and the threads of a plug partially threaded therein whereby the shell will be moved into and out of the base by a plug threaded therein, and a contact arranged to be engaged by said shell when the shell is in its inner position, said con- 70

75

tact being spaced from the shell when the shell is in its outer position.

7. In an electric socket having a center terminal and a screw shell, the shell and the pocket having cooperating parts whereby the shell is moved into and out of the socket upon rotation relative thereto, said parts being engaged when the shell is in its outer position and serving to prevent rotation of said shell, the resistance to rotation of the shell being less than the friction between the threads of the shell and the threads of a plug partially threaded therein whereby the shell will be moved into and out of the socket by a plug threaded therein, a member of insulating material carried by the shell for preventing short-circuit of the socket when the shell is in its outer position, said member permitting contact between the center terminal of the socket and the center contact of a plug threaded in the shell when the shell is in its inner position, and a contact engaged by the shell when the shell is in its inner position, said contact being spaced from the shell when the shell is in its outer position.

25. In an electric socket having a center terminal and a screw shell, the shell and the socket having cooperating parts whereby the shell is moved into and out of the socket upon rotation relative thereto, said parts being engaged when the shell is in its outer position and serving to prevent rotation of said shell, the resistance to rotation of the shell being less than the friction between the threads of the shell and the threads of a plug partially threaded therein whereby the shell will be moved into and out of the socket by a plug threaded therein, a member of insulating material carried by the shell for preventing short-circuit of the socket when in its outer position, said member having a contact extending through the center thereof and adapted to make contact with the center terminal of the socket and with the center contact of a plug threaded in the shell, said contact being spaced from the center terminal of the socket when the shell is in its outer position, and means for limiting the outward movement of the shell.

9. In an electric socket having a center terminal and a screw shell for cooperation with a plug threaded in the shell, the shell and the socket having cooperating parts whereby the shell is moved into and out of the socket upon rotation relative thereto, said parts being engaged when the shell is in its outer position and serving to prevent rotation of said shell, the resistance to rotation of the shell being less than the friction between the threads of the shell and the threads of a plug partially threaded therein whereby the shell will be moved into and out of the socket by a plug threaded therein, a member of insulating material at the bottom of the shell for preventing short-circuit of the socket when the shell is in its outer position, and means for limiting the outward movement of the shell.

10. In an electric socket having a center terminal and a screw shell for cooperation with a plug threaded in the shell, the shell and the socket having cooperating parts whereby the shell is moved into and out of the socket upon rotation relative thereto, said parts being engaged when the shell is in its outer position and serving to prevent rotation of said shell, the resistance to rotation of the shell being less than the friction between the threads of the shell and the threads of a plug partially threaded therein whereby the shell will be moved into and out of

the socket by a plug threaded therein, and a contact engaged by the shell when the shell is in its inner position, said contact being spaced from the shell when the shell is in its outer position.

11. In an electric socket, a base, a center terminal for co-operating with the center contact of a plug to be inserted in said socket, a sleeve rotatably and axially movable in the base, a screw shell carried by said sleeve and movable therewith into and out of the base, cooperating parts on the sleeve and the base arranged to effect axial movement of the sleeve into and out of the base upon rotation thereof relative to the base, the resistance to rotation of the sleeve being less than the friction between the threads on the screw shell and the threads on the plug partially threaded into the screw shell whereby the sleeve is rotated in the direction to move it inward by threading the plug into the shell and whereby the sleeve is rotated in the direction to move it outward by threading the plug out of the shell, and a contact engaged by the shell when the shell is in its inner position, said contact being spaced from the shell when the shell is in its outer position.

12. In an electric socket, a base, socket terminals comprising a screw shell and a center contact, said screw shell being rotatably and axially movable in the base, a part on the base engaging the threads on the outside of the screw shell whereby the shell is moved into and out of the base upon rotation therein, the friction between said part of the base and the screw shell being less than the friction between the screw shell and a plug threaded therein whereby the shell may be rotated by the plug, means stopping outward movement and rotation of the shell prior to disengagement of said part and the shell whereby the plug may be unthreaded from the shell, line contacts, means effective upon movement of the shell to its inner position for completing a circuit from one of the line contacts to one of the socket terminals, said circuit being open when the screw shell is in its outer position, and means connecting the other line contact and socket terminal.

13. In an electric socket, a base, socket terminals comprising a screw shell and a center contact, said screw shell being rotatably and axially movable in the base, cooperating parts on the screw shell and base arranged to effect axial movement of the screw shell into and out of the base upon rotation of the screw shell in the base, the resistance to rotation of the screw shell being such that the screw shell is rotated in the direction to move it inward by threading a plug into the shell and such that the screw shell is rotated in the direction to move it outward by threading the plug out of the shell, means stopping the outward movement and rotation of the shell prior to disengagement of said parts whereby the plug may be unthreaded from the shell, line contacts, means effective upon movement of the shell to its inner position for completing a circuit from one of the line contacts to one of the socket terminals, said circuit being open when the screw shell is in its outer position, and means connecting the other line contact and socket terminal.

14. In an electric socket, a base having a recess, socket terminals including a center terminal for co-operating with the center contact of a plug to be installed in said socket, and a screw shell, the screw shell being rotatably and axially
